ATTORNEY

UNITED STATES PATENT OFFICE.

FLOYD C. HEDRICK, OF KENTLAND, INDIANA.

CARD-HOLDER.

1,270,412.

Specification of Letters Patent. Patented June 25, 1918.

Application filed September 25, 1916. Serial No. 122,094.

To all whom it may concern:

Be it known that I, FLOYD C. HEDRICK, a citizen of the United States, residing at Kentland, in the county of Newton and State 5 of Indiana, have invented certain new and useful Improvements in Card-Holders, of which the following is a specification.

This invention relates to card holders, and particularly to holders for price tickets for 10 the purpose of attaching them to merchandise on sale, on which cards any information desired may be written. The particular object of the invention being to provide a ticket holder of a very simple and convenient form made of wire and adapted to 15 hold the ticket by spring pressure, and in turn to be secured in a similar manner to the merchandise, there being no sharp points on the holder to prick the fingers of persons 20 handling the merchandise or itself doing damage thereto.

The invention furthermore can be made very cheaply and in such manner as to securely hold itself in position and the ticket 25 in place and permit the latter to be removed should it become broken, soiled or the data thereon require changing without removing the holder from the article to which it is attached.

With these objects in view the invention 30 consists of the novel construction herein-after described, pointed out in the claim, and illustrated in the accompanying drawings, in which—

Figure 1 is a face view showing the holder 35 attached to a piece of cloth and a ticket secured thereto,

Fig. 2 is a similar view of the opposite side 40 of the ticket holder and ticket,

Fig. 3 is a vertical central section on the line 3—3 of Fig. 1,

Fig. 4 is a perspective view of the ticket 45 holder, and

Fig. 5 is a similar view of one of the ticket gripping elements of the ticket holder.

In the drawing, 10 indicates the ticket holder complete, and as clearly shown in Fig. 4, is made of a single length of wire bent centrally upon itself to form a relatively broad loop 11 of substantially semi-circular form, the arms 12 of which extend substantially parallel for a suitable distance and are then given a quick bend outwardly as at 13 and projected in the opposite direction parallel to and in the same plane with the arms 12. These oppositely projecting

portions 14 are of equal length and extend nearly to the crown of the loop 11 and are then bent outwardly again at right angles to the portions 14 to form lateral projections 15 which are preferably in the same line and are much shorter than the portions 14 being bent back upon themselves to provide gripping fingers 16 that contact with the projections 15 and in front of the same, the ends of the fingers being bent downwardly and backwardly to bear on the under side of said fingers as shown at 17. The arms 12 between the loop 11 and the loops 13 are preferably crimped as indicated at 18 to increase friction between the holder and the article to which it is attached and hence the holding power.

In use, a price or other ticket A is inserted 50 between the portions 15 and the fingers 16, which being normally in contact are pressed apart upon the insertion of the ticket and by reason of the resiliency of the loops 19 grip the ticket with sufficient firmness to prevent the same slipping from the fingers 16 but not so tight as to prevent ready removal therefrom when desired. A holder is attached to the article of merchandise 13 by inserting the edge thereof between the arms 12 and 14, the arms 12 with the loop 11 passing on one side of the article and the arms 14 on the other side until the edge of the article A engages the loops 13 connecting said arms. As previously stated arms 12 and 14 being 55 in the same plane, the entrance of goods between them will cause arms 12 to separate from the arms 14 a distance depending on the thickness of the material B but owing to the resiliency of the arms and the loops 13 they will tend to return to their normal position, which tendency serves to clamp the ticket holder to the article with sufficient friction to prevent its slipping therefrom while being handled, the crimps 18 serving to further increase the gripping power of the 60 ticket holder.

From the above it will be seen that the ticket holder is simple and can be made with little trouble and at a small expense, and serves to respectively retain a ticket upon 65 the edge of an article of merchandise and be itself attached thereto without danger of becoming misplaced and without the necessity of puncturing the merchandise which is liable to cause the latter to be torn when 70 the same consists of a delicate fabric. Furthermore, this ticket holder may be employed

as a clip for securing sheets of paper, cards, and the like and applying a tag thereto.

What I claim is:

A card holder formed of a single length of spring wire bent backwardly and forwardly upon itself to form four substantially parallel arms lying in the same plane, the innermost arms adapted to be sprung outwardly from said outermost arms, crimps on the innermost arms, and card gripping fingers on the terminals of the outermost arms, said fingers being formed by bending the ends of the wire outwardly in the plane of the arms and then backwardly each upon and

in contact with itself and finally bending the 15 terminals of said wire again outwardly forming thereby an eye in the terminal of each finger to provide a relatively broad faced gripping surface for engaging the face of a card and holding it securely against the 20 outwardly bent portion of the finger.

In testimony whereof I affix my signature in presence of two witnesses.

FLOYD C. HEDRICK.
